UNITED STATES PATENT OFFICE.

HARRY L. BEACH, OF COSHOCOTON, OHIO.

SIGN.

No. 855,747.

Specification of Letters Patent.

Patented June 4, 1907.

Application filed November 10, 1906. Serial No. 342,898.

To all whom it may concern:

Be it known that I, HARRY L. BEACH, a citizen of the United States, residing at Coshocton, in the county of Coshocton and 5 State of Ohio, have invented a new and useful Sign, of which the following is a specification.

This invention relates to advertising devices and more particularly to signs.

10 The primary object is to provide a novel, simple and unique article of manufacture that will attract the eye, is easy and cheap to manufacture and may be readily secured to a support, the structure being such that it 15 can be shipped with all the parts assembled.

The preferred form of construction is illustrated in the accompanying drawings, wherein.

20 Figure 1 is a view in elevation of the sign; Fig. 2 is a longitudinal sectional view on the line 2—2 of Fig. 1; Fig. 3 is a sectional view on the line 3—3 of Fig. 1; Fig. 4 is a detail sectional view on the line 4—4 of Fig. 3.

25 Similar reference numerals designate corresponding parts throughout the several figures of the drawings.

In the embodiment illustrated a body plate 5 is employed that is preferably constructed of comparatively heavy sheet metal 30 so that it will not readily bend, one end of this plate being off-set to provide a flange 6 adapted to be placed against a wall or support, said flange having openings 7 there-through to receive securing devices. The 35 body plate 5 is provided with a central opening 8 which may be of any shape desired, that shown being elliptical.

A rotatable plate 9, also preferably constructed of sheet metal, is mounted in the 40 opening. The bearings for this plate consist of socket elements 10 and pintle elements 11. The socket elements 10 comprise heads 12 having tapered sockets 13 in their outer ends and rearwardly projecting 45 straps 14. The heads 12 are located in notches 15 formed in the body plate 5 on opposite sides of the opening 8, the straps 14 straddling the plate and being secured thereto by suitable rivets 16. The pintle elements 50 11 comprise heads 17 having tapered

outer ends 18 that are journaled in the sockets 13. These heads are located in notches 19 formed in the opposite sides of the rotatable plate 9 and alined with the notches 15 of the body plate. The heads 17, 55 furthermore, are provided with straps 20 that straddle the opposite portions of the rotatable plate and are secured thereto by suitable rivets 21.

It will be evident that this is an exceedingly simple structure, one that can be shipped in assembled condition, cheaply manufactured and requiring only the use of a few nails or screws to fasten it to a support. Advertising matter may be placed both on 60 the body plate and the rotatable plate, as shown. This rotatable plate is preferably compoundly curved substantially as illustrated in Fig. 2, and if placed where it will be struck by currents of air it will revolve, thus 65 attracting attention to the sign. In advertising many articles of manufacture, the rotatable plate can be made of the shape of and represent such articles of manufacture. The journal bearings for the rotatable plate are 70 exceedingly simple and peculiarly effective, for they serve to strengthen both plates as will be evident. Moreover, by having the heads of the bearing elements located in 75 notches, as shown, the rotatable plate can be 80 made of a size to practically fill the opening in the body plate, allowing sufficient clearance only to avoid interference.

Having thus described my invention, what I claim as new and desire to secure by Letters 85 Patent, is:—

As an article of manufacture, a sign comprising a body plate having means for securing to a support, said plate being provided with an opening and notches located 90 on opposite sides of the opening, a rotatable plate operating in the opening and having notches in its opposite sides alined with the notches of the body plate, and journal bearings for the rotatable plate comprising socket 95 elements having heads provided with sockets in their ends and straps projecting from the heads, and pintle elements having tapered heads that engage in the sockets, said tapered heads having straps projecting there- 100

from, certain of said elements having their heads located in the notches of the body plate and their straps straddling and secured to said plate, the co-acting elements having their heads located in the notches of the rotatable plate and their straps straddling and secured to said rotatable plate.

In testimony, that I claim the foregoing as my own, I have hereto affixed my signature in the presence of two witnesses.

HARRY L. BEACH.
